ATTORNEY

UNITED STATES PATENT OFFICE.

JOHN B. WORD, OF LATROBE, CALIFORNIA.

LEVEL.

1,175,327.

Specification of Letters Patent. Patented Mar. 14, 1916.

Application filed June 15, 1915. Serial No. 34,176.

To all whom it may concern:

Be it known that I, JOHN B. WORD, a citizen of the United States, residing at Latrobe, in the county of El Dorado and State 5 of California, have invented certain new and useful Improvements in Levels, of which the following is a specification.

My invention relates to that class of levels in which the necessary indication is effected 10 by the movement of a freely swinging weighted member.

My invention has for its object the provision of a simple, accurate, sensitive and durable level adapted to indicate from all 15 sides or surfaces of the stock, both the horizontal and vertical planes, and any angle of deviation therefrom.

To this end my invention consists in the novel level which I shall hereinafter fully 20 describe, by reference to the accompanying drawings in which—

Figure 1 is a side elevation of my level. Fig. 2 is a horizontal longitudinal section on the line $x-x$ of Fig. 1. Fig. 3 is a vertical cross section, enlarged, on the line $y-y$ 25 of Fig. 1. Fig. 4 is an elevation of the freely swinging weighted member or spider.

1 is the stock of the level, said stock being of any suitable material and shape, being 30 here shown as of I-beam cross section. At its middle the stock is formed with a socket 2, which opens to each side through sight apertures 3 covered with glass crystals 3', and it is also exposed top and bottom 35 through sight apertures 4, covered with glass 4'. Behind the crystals 3', one on each side, is a plate 5. On the outer face of each plate is a dial 6 graduated in degrees throughout the circle. In these plates 5 is rotatably 40 mounted by any suitable delicate bearings, a shaft 7, on each end of which is a hand 8 adapted to play over the dial.

The shaft 7 is the axis of a spider member 9, the rim 10 of which is graduated in degrees 45 which are exposed to view through the sight apertures 4 in the top and bottom of the stock 1.

The spider member carries a short tube 11, which contains a freely shifting weight 50 12. This weight, in its best form, is a liquid body, quicksilver being well adapted for the purpose. The tube 11, which is here shown as made of glass, is carried by the spider member by suitable connections, such

as the clamp sockets 13. The tube 11 is 55 mounted sufficiently near the periphery of the spider to provide for efficient leverage and said tube is covered lengthwise. A point to be especially noted in this regard is that the tube 11 is covered on an arc of 60 greater radius than that of the spider-rim and it is therefore somewhat straighter. This results in increased sensitiveness of the shifting weight, the liquid globule tending to start quicker upon the change of the level. 65

The position of the hands 8 is, of course, diametrically opposite to that of the center of gravity of the weight.

In order to provide for any required adjustment the side plates 5 are carried in a 70 ring 14 which is adapted for a slight movement on its axis in the socket 2 of the stock. On the outer face of this ring at one side are rack teeth 15 (Fig. 2) with which engages the thread of a screw 16 set into the 75 stock, and held by a small set screw 17. By means of the screw 16 the position of the ring 14 in its seat may be adjusted.

18 are spring snap rings to hold ring 14 in its seat, and, as shown, the side crystals 3' 80 are seated in said ring 14.

I claim:—

1. A level comprising a stock having a socket with sight apertures to the exterior of both sides and top and bottom of said 85 stock; a dial-plate in each of said side apertures; a spider freely rotatably mounted within said socket and carrying a hand on each end of its axis, playing over said dial-plates, said spider having a rim graduated 90 in degrees and exposed to view through the sight apertures in the top and bottom of the stock; a curved tube carried by said spider; and a freely shifting weight within said tube. 95

2. A level comprising a stock having a socket with sight apertures to the exterior of both sides and top and bottom of said stock; a carrying ring mounted rotatably in said socket and having gear-teeth in the exterior periphery thereof; means for adjusting said ring on its axis comprising a rotatably mounted stem provided with a screw thread for engagement with said teeth; a dial-plate carried in each side of the ring 100 and exposed to view through the side apertures of the socket of the stock; a spider freely rotatably mounted by its axis in the 105

side plates and carrying a hand on each end of said axis, playing over said dial-plate, said spider having a rim graduated in degrees and exposed to view through the sight apertures in the top and bottom of the stock; a curved tube carried by said spider; and a freely shifting weight within said tube.

In testimony whereof I have signed my name to this specification in the presence of two subscribing witnesses.

JOHN B. WORD.
